DESIGN FOR A TOP FOR A WATER COOLER OR SIMILAR ARTICLE

Albert A. Ralston and Dean C. Rinehart, Fort
Wayne, Ind., assignors to General Electric Com-
pany, a corporation of New York

Application February 8, 1941, Serial No. 98,856

Term of patent 14 years

To all whom it may concern:

Be it known that we, Albert A. Ralston and
Dean C. Rinehart, citizens of the United States,
residing at Fort Wayne, in the county of Allen,
State of Indiana, have invented a new, original,
and ornamental Design for a Top for a Water
Cooler or Similar Article, of which the following
is a specification, reference being had to the
accompanying drawing, forming a part thereof.

The single figure of the drawing is a perspec-
tive view of a top, for a water cooler or similar
article embodying our new design.

We claim:

The ornamental design for a top for a water
cooler or similar article, substantially as shown.

ALBERT A. RALSTON.
DEAN C. RINEHART.
